Primary Examiner—Charles A Rademaker*(74) Attorney, Agent, or Firm*—Lyman H. Moulton(57) **CLAIM**

The ornamental design for an anti-snore mouthguard, as shown and described.

DESCRIPTION

FIG. 1 is a rear perspective view of an anti-snore mouthguard showing my new design;

FIG. 2 is a top perspective view thereof;

FIG. 3 is a bottom perspective view thereof;

FIG. 4 is a front perspective view thereof;

FIG. 5 is a right perspective view thereof;

FIG. 6 is a left perspective view thereof; and,

FIG. 7 is a front perspective view of a modified embodiment of the design shown in FIG. 1 through 6, all other views being substantially identical.
